[57] CLAIM

The ornamental design for a fishing rod handle, as shown and described.

DESCRIPTION

FIG. 1 is a side elevational view of the fishing rod handle embodying my new design, the opposite side being a mirror image thereof;

FIG. 2 is a top plan view of the fishing rod handle;

FIG. 3 is a bottom plan view;

FIG. 4 is a front end elevational view thereof; and,

FIG. 5 is a rear elevational view of the fishing rod handle.
